UNITED STATES PATENT OFFICE.

JESUS E. FIMBRES, OF NOGALES, ARIZONA.

DESIGN FOR A STOCKING.

Application filed August 26, 1927. Serial No. 23,217. Term of patent 14 years.

To all whom it may concern:

Be it known that I, JESUS E. FIMBRES, a citizen of the United States of America, residing at Nogales, in the county of Santa Cruz and State of Arizona, have invented a new, original, and ornamental Design for a Stocking, of which the following is a specification, reference being had to the accompanying drawing, forming a part thereof.

The figure is a perspective view of a stocking showing my new design.

I claim:

The ornamental design for a stocking as shown.

JESUS E. FIMBRES.
